UNITED STATES PATENT OFFICE

2,594,013

DUAL TONE REED HORN

Harry Hahn, Bronx, N. Y., assignor to Steelcraft
Tool Manufacturing Corp., New York, N. Y.

Application January 28, 1950, Serial No. 141,062

2 Claims. (Cl. 116—139)

1

This invention relates to reed horns and pertains particularly to a dual tone reed horn adapted to be mounted on a bicycle handle bar or the like.

One object of the present invention is to provide a reed horn including dual reeds and dual horn sections in order to effect dual tones upon a single blast of air past said reeds.

Another object of the present invention is to provide a reed horn including a single reed and dual horn sections, each horn section receiving the same tone from said reed but being adapted to alter said tone to thereby effect dual tones upon a single blast of air past said single reed.

Another object of the present invention is to provide novel horn reeds which are adapted for facilitated entrance into and self-retention in the reed passages of reed horns.

Still another object of the present invention is to provide a novel reed horn formed as a single die casting and having integral therewith one-half of the bracket required for mounting the horn on a bicycle handle bar or the like.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an end view of the first embodiment of the invention but with bulb omitted to illustrate the disposition of the dual reeds in the neck portion.

Fig. 2 is a sectional view taken along the lines 2—2 in Fig. 1, but with the bulb added.

Fig. 3 is a sectional view taken along the lines 3—3 in Fig. 2 and illustrates features of construction of the integral mounting element.

Fig. 4 is an isometric view of a form of dual reed construction employed in the first embodiment.

Fig. 5 is a side elevational view of an independently formed mounting element adapted to associate with the integral mounting element.

Fig. 6 is an end view of the element seen in Fig. 5.

Fig. 7 is an end view of a second embodiment of the invention and shows the disposition of a single reed construction in the reed passage.

Fig. 8 is a sectional view taken along the lines 8—8 in Fig. 7, but with the integral mounting

2

element shown in full and the bulb or air blasting means indicated by dot and dash lines.

Fig. 9 is an isometric view of a form of single reed construction employed in the second embodiment.

Fig. 10 is another longitudinal sectional view similar to Fig. 2, but illustrating the horn constructed in accordance with a still further modification of the present invention.

10 With reference to the drawings in more detail, and particularly to Figs. 1 to 6, it will be seen that the first embodiment of the invention provides a horn 10 having first and second horn sections 11 and 12, respectively, and a neck section 13.

15 Said horn is of a one-piece construction and is preferably die cast. As best seen in Fig. 2 the said first horn section 11 is of greater length than the mentioned second horn section 12 and as a result said sections are differently pitched. 20 However, the neck section 13 is common to the inlets to both the horn sections.

Disposed and retained in the neck section 13, in a manner to be described hereinafter, is a reed construction 14 having a low pitched reed

25 15 and a high pitched reed 16 formed therein. Said reed construction 14 as seen in Fig. 4, also, is preferably of a resilient metal and is formed with an upper portion 17, in which the low pitched reed 15 is formed, folded in spaced relation over a lower portion 18, in which the high pitched reed 16 is formed. This arrangement is such that the reed construction, when outside the neck section 13, is too large to slide into the neck section but may be compressed and inserted into the neck section. When permitted to respond to the inherent resilience of the material of which it is fabricated, the reed construction 14 is self-retaining in the neck section 13, with each of said reeds directed to its related horn section.

40 Provided on the outer periphery of the neck section 13 is a plurality of annular ribs 20 which ribs are adapted to assist in holding on the neck section a bulb 21 of rubber or like material,

45 which bulb when squeezed introduces a blast of air through the neck section and past said reeds to thereby set said reeds vibrating to thusly produce two differently pitched sounds. Now, since each of said reeds is directed to a related one of 50 said horn sections, each horn section will effect an amplification of the sound produced by that reed directed thereto.

55 Cast integral with the horn and adapted to assist in the mounting thereof on a bicycle handle bar or the like is a mounting element 22 (Figs.

2 and 3) which element is formed with a standard 23 having reinforcing ribs 24, and forwardly and rearwardly extending arms 25 and 26, respectively, each having a threaded bolt hole 27.

Adapted to cooperate with said integral mounting element 22 is an independently formed mounting element 30 (Figs. 5 and 6), which element is also provided with forwardly and rearwardly extending arms 31 and 32, respectively, having threadless bolt holes 33 therein. It is well known how said integral and independently formed elements, when made to embrace a round or similarly formed structure such as a bicycle handle bar, may be bolted together for effecting the mounting of said horn 10.

A second embodiment 35 of the invention is shown in Figs. 7 to 9, which is similar to the first in that it, too, is of a one-piece die cast construction and includes a first horn section 11 and a second horn section 12, a neck section 13, a plurality of annular ribs 20 formed on the outer periphery of the neck section for facilitating the fastening thereto of a bulb 21, and an integrally formed mounting element 22. Whereas the inlets into both the horn sections 11 and 12 of the first embodiment were of the same restrictive dimensions, the inlets into the horn sections of the present embodiment are differently restrictive. That is, the inlet 36 to the second horn section 12 in this embodiment is cast smaller than that to the first horn section 11.

Also adapted to be disposed and retained in the neck section 13 of the present embodiment is a modified resilient reed construction 37 (Figs. 7, 8 and 9) which includes a single reed 38 formed in a flat portion 39 thereof, and longitudinally and downwardly extending arcuate side portions 40. To insert this modified reed construction into the neck section 13 the said side portions 40 are pressed together. This makes the width-wise dimension of the reed construction smaller than the internal diameter of the neck section and permits the construction to be inserted thereinto. Once in the neck section the resilience of the reed construction is sufficient to retain it therein.

Inasmuch as the just described embodiment includes but a single reed 38, squeezing of the bulb 21 to force air past the reed effects but a singly pitched sound. However, the different lengths of the horn sections 11 and 12 and the restrictive inlet 36 to the horn section 12 so affect the mentioned singly pitched sound as to provide a dual tone.

In the modification of the invention shown in Fig. 10, there is mounted in each of the horn sections 11 and 12 closely adjacent the neck section 13 a tubular plug 40. The plugs 40 are preferably formed of cork but may be formed of rubber or a synthetic resinous material. Mounted in position through each of the plugs 40, there is a reed member 41. The reed members are of different lengths so as to produce a different tone when air is forced past the reed members 41 by squeezing the bulb 21.

In other respects the forms of the invention

shown in Figs. 7 to 9 and in Fig. 10 are similar to the form shown in Figs. 1 to 6 and like reference numerals are used to identify like parts throughout.

5 While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

- 15 1. The combination with a reed horn including a pair of differently pitched horns, a neck section common to the inlets of said horns, and means for blasting air through said neck section; of a one-piece resilient construction comprising one portion folded over a second portion in spaced relation, a reed formed in said one portion and a differently pitched reed formed in said second portion, said portions being compressible together to permit the insertion of the construction in the neck section of said horn, and the resilience of said construction being effective for the retention thereof in said neck section with each of said reeds directed toward a related one of said horn inlets.
- 20 2. A reed horn comprising a pair of integral and differently pitched horns, a neck section common to the inlets of both of said horns, means for blasting air through said neck section; a one-piece resilient construction comprising one portion folded over a second portion in spaced relation, a reed formed in said one portion and a differently pitched reed formed in said second portion, said portions being compressible together to permit the insertion of the construction in the neck section of said horn, the resilience of said construction being effective for the retention thereof in said neck section with each of said reeds directed toward a related one of said horn inlets; a plurality of annular ribs formed on the outer periphery of said neck section to secure the air blasting means thereto; a mounting element formed integral with said horns; and an independent mounting element associated with said integral element.
